[57] CLAIM

The ornamental design for toy digger, as shown and described.

DESCRIPTION

FIG. 1 is a side elevational view of a toy digger showing my new design;

FIG. 2 is another side elevational view thereof showing the forward members in an alternate position;

FIG. 3 is a top plan view thereof;

FIG. 4 is a front elevational view thereof;

FIG. 5 is a rear elevational view thereof;

FIG. 6 is a bottom plan view thereof; and

FIG. 7 is a side elevational view thereof from the opposite side to that shown in FIG. 1.
